UNITED STATES PATENT OFFICE.

JACOB M. ESSER, OF MADISON, WISCONSIN.

HOSE-REEL.

1,117,357.

Specification of Letters Patent.

Patented Nov. 17, 1914.

Application filed May 1, 1914. Serial No. 835,762.

To all whom it may concern:

Be it known that I, JACOB M. ESSER, a citizen of the United States, residing at 532 West Dayton street, Madison, in the county 5 of Dane and State of Wisconsin, have invented a new and useful Hose-Reel; and I do hereby declare the following to be a full, clear, and exact description of the invention, such as will enable others skilled in the art to 10 which it appertains to make and use the same.

This invention relates to a new and useful hose reel.

An object of the invention is to provide 15 a device of this nature, designed more especially to be suspended from the ceiling of a garage or the like, for not only rendering the hose handy for use for washing off the automobiles, but also enabling the person 20 in charge to wash the floor of the garage.

The invention aims as another object to provide means upon the reel, whereby upon 25 unwinding the hose spring means is put under tension, so that when the user has finished the same, it will automatically rewind upon the reel.

As a further object, it is the aim to provide 30 a novel fluid tight universal joint between the water supply tube and a pipe extension of the hollow axle of a wheel, so that the reel may easily revolve.

One of the features of the invention is the provision of means for permitting the 35 reel to be held in adjusted positions as the hose is unwound or unreeled.

In practical fields the details of construction may be subjected to alterations, falling 40 within the scope of what is claimed.

The invention comprises further features and combination of parts, as hereinafter set forth, shown in the drawings and claimed.

In the drawings:—Figure 1 is a view 45 in side elevation of the improved hose reel as suspended from the ceiling of a garage. Fig. 2 is a similar view showing the hose removed, more clearly defining the skeleton reel. Fig. 3 is a view in side elevation showing parts of the reel in longitudinal section. Fig. 4 is an end elevation of the 50 hose reel. Fig. 5 is an enlarged detail sectional view through the universal fluid tight joint, between the water main and the tubular extension of the hollow shaft of the reel.

Referring more especially to the drawings, 55 1 and 2 designate the hangers or

brackets (which may be in the form of castings or the like) designed to be fastened to any suitable stationary support, for instance, as in the present case to the ceiling 60 3 of a garage. Mounted in bearings 4 of the hangers or brackets is a tubular shaft 5, one end of which is provided with a flange 6 to engage the bracket 2 to prevent endwise movement of the shaft. Extending 65 into one end of the hollow shaft is a pipe or tubular member 7 having an elbow 8, which extends through the wall of the tubular shaft and is provided with an extension 9, to which the hose 10 is connected. The 70 hose reel comprises the end members 11 and 12, which are provided with radial arms 13. The end members or disks 11 and 12 are connected by the rods 14, on which the hose winds or reels. The end members 75 11 and 12 are provided with flanges 15, through which the bolts or screws 16 extend and into the outer shaft, thereby fastening the end members to rotate with the shaft. It will be observed that the pipe or tubular 80 member 7 also rotates with the shaft 5. Owing to the members 11 and 12 being interposed between the brackets or hangers 1 and 2, and the flanges 15 being secured to the shaft longitudinal movement of the shaft 85 is prevented.

Arranged on the interior of the tubular shaft is a coil spring 18, one end of which is secured at or attached to the elbow 8 as shown at 19, the other end of the spring 90 is anchored at 20 in the bearing or hanger or bracket 1. This spring is so arranged and the hose so wound upon the reel, that when the hose is unreeled by pulling upon the end 22, the hose will unreel against the 95 tension of the spring 18, the pawl 23 acting to engage one or another of the teeth 24 of the ratchet 25, so as to hold the hose partially or entirely unreeled. The pawl is pivoted at 26, and connected to the same 100 is a cord 27 having a handle 28. Upon exerting a pulling action upon the cord 27, a pawl 23 is raised against the action of the spring 29, thereby releasing the ratchet, in which case owing to the action of the spring 105 18, the hose will be again reeled or wound upon the reel. The ratchet is fastened to the end member or disk 11 by virtue of the screws 30.

The pipe or tubular member 7 has a 110 flanged end 31, to which a gasket 32 is fastened, by means of the plate 33 and screws

2

34. This flanged end of the pipe or tube 7 with its gasket 32 are swiveled between the enlarged or flanged ends 35 and 36, which are threaded together as at 37, there being a gasket 38 interposed. The flanged end of the pipe or tube 7 seats in the recess 39 of the enlarged or flanged end of the coupling member 40, while the gasket 32 seats in the recess 41 of the enlarged or flanged end 36 of the other coupling member 42. It will be observed that as the reel rotates in one direction or the other, the pipe or tube 7 moves therewith and swivels between the connected ends of the coupling members 40 and 42. The water supply pipe or tube 43 is threaded or otherwise connected at 44 to the coupling member 42 so as to enable the water to pass through the hose. The coupling member 40 is provided with an oil cup 45, which lubricates where the flanged end 31 revolves.

The invention having been set forth, what is claimed as new and useful is:—

1. A hose reel comprising a pair of hang-
ers, a hollow shaft mounted in bearings of
the hangers, a reel connected to the shaft
to rotate therewith, a tubular pipe or mem-
ber extending into the shaft and provided
with pipe fittings connected to the shaft
whereby the tubular pipe may rotate there-
with, said tubular pipe having a swiveled
connection with a water supply pipe, a hose
on the reel having one end connected to the
pipe fittings, a coil spring on the interior of
the shaft having one end connected to the
pipe fittings and the other end to one of the
hangers, and means for holding the reel in
adjusted position when the hose is partially
or entirely unwound, said spring acting to
rewind the hose when said means are re-
leased.

2. A hose reel comprising a pair of hang-

ers, a hollow shaft mounted in bearings of
said hangers, a reel rotatable with the shaft
and provided with a hose, connections with
one end of the hose and passing through one
end of the hollow shaft and provided with
swiveled connections to a water supply pipe,
spring means inside of the tubular shaft
against the action of which the hose is un-
reeled, a spring pawl and ratchet mechanism
for holding the reel in adjusted positions
when the hose is unreeled.

3. A hose reel comprising a pair of hang-
ers, a hollow shaft having a flange at one
end swiveled in a bearing of one of the
hangers and having its other end mounted
in a bearing of the opposite hanger, a reel
comprising end disks provided with flanges
bolted to the hollow shaft, rods connecting
said disk, a hose wound upon the reel, con-
nections between one end of a hose and a
water supply pipe passing through one end
of the hollow shaft, said connections com-
prising pipe fittings, one of which passes
through the wall of the hollow shaft and
anchors the connections to rotate with the
shaft, a spring coiled in the hollow shaft
having one end connected to one of the fit-
tings, and the other end connected to one of
the hangers against the action of which the
hose is unreeled, and a spring tensioned
pawl and ratchet mechanism interposed be-
tween one of the disks and one of the
hangers, to hold the reel in adjusted position
against the action of the spring when the
hose is unreeled.

In testimony whereof I have signed my
name to this specification in the presence of
two subscribing witnesses.

JACOB M. ESSER.
